UNITED STATES PATENT OFFICE

BÉLA ROSENTHAL, OF BUDAPEST, HUNGARY

POWDER BOX

Application filed November 18, 1929, Serial No. 408,103, and in Hungary August 7, 1929.

Powder boxes are known in ladies' beauty culture, in which a certain quantity of loose powder is delivered through the holes in the lid of the powder container after the box lid has been opened, by turning the powder container by hand, in which the loose powder is whirled up by fixed blades or scoops arranged in the powder container and forced through the holes. The handling of such boxes is however inconvenient and requires a certain amount of skill.

As compared with powder boxes of this type, the invention relates to a powder box, the essential feature of which consists in that a rotatably mounted blade- or vane-wheel is arranged in a stationary powder container and positively connected with a casing movable in rectilineal direction enclosing the box, so that by the movement of the casing in relation to the box the blade- or vane-wheel is caused to rotate, resulting in the delivery of the loose powder. Consequently on the opening of the box the powder is delivered at the same time.

Two embodiments of the invention are illustrated by way of example in the accompanying drawing in which:—

Fig. 1 is a longitudinal section through one form of construction.

Fig. 2 is a top plan view of the construction shown in Fig. 1.

Fig. 3 is a cross section of the construction shown in Fig. 1.

Fig. 4 shows a second form of construction in perspective view.

According to the form of construction shown in Figs. 1 to 3 the box *b*, enclosing the actual powder container *a*, is surrounded by a casing, composed of two like parts *c* and *d*. These parts extend through the box *b* and can be moved apart a certain distance the movement being limited by studs *e*; the box is then open (Figs. 1 and 2). On pushing together the casing parts *c* and *d* their two inner edges abut, the box being thereby closed.

A pin *f* is rotatably mounted in the bottom of the box *b* and a spur wheel *g* is keyed on this pin. The pin *f* projects through an opening in the bottom of the powder container *a* and a blade- or vane-wheel *h* is fastened on

its upper part. The powder container *a* is closed at the top by a perforated lid *i*, held in position by two resilient tongs *l* fastened on the casing *k*, surrounding the powder container *a*. A metal mirror *n* is also mounted on the lid *i* by means of a spring hinge *m*.

The pin *e* limiting the movement of the casing part *d* is preferably also utilized as pivot pin for a rack *o*, meshing with the spur wheel *g*, a spring *p* being provided in known manner for ensuring that the spur wheel and the rack remain in permanent engagement.

From the foregoing it will be seen that, each time the casing part *d* is displaced in relation to the box *b*, the blade- or vane-wheel *h* will be rotated by the positive connection between the spur wheel *g* and the rack *o*, which rotation results in the powder being delivered through the holes in the lid *i*. If therefore the casing parts *c* and *d* are moved apart, so that the powder container is accessible, the metal mirror *n* springs open automatically into the position shown in Fig. 3, and the pad placed on the lid *i* receives sufficient powder for a single use.

Instead of the positive connection, consisting of a spur wheel and a rack, between the box and the one casing part actuating same, a positive connection composed of a ratchet wheel and a ratchet rack may be employed. Such a construction presents the advantage, that the turning of the blade or vane wheel and therefore the delivering of the loose powder can only be effected by the movement of the corresponding casing part in one direction, for example, when opening.

The form of construction shown in Fig. 4 differs from that described only in that the box *b* is arranged in a casing *r* open on one side. The box *b* is pulled out of the casing by means of a tab *s*. Instead of a tab a knob may be provided. In this form of construction the above described positive connection between the box *b* and the casing *r* is also employed, so that on opening the box the loose powder is delivered. A depression is preferably provided in the lid of the powder container, in which a lip-stick (rouge) *t* is placed

I claim:—

1. A powder box, comprising in combina-

ton, a rigid powder container, a lid on said container having holes for delivering the powder, a blade- or vane-wheel rotatably mounted in said container, a rectilinearly displaceable casing surrounding said powder container, and means connecting said casing with said wheel adapted to rotate said wheel on the opening of the box.

2. A powder box as specified in claim 1, comprising in combination with the casing and the blade- or vane-wheel, a boss on said wheel, a tooth wheel on said boss, and a rack connected to said casing, adapted to engage in said tooth wheel.

15 3. A powder box as specified in claim 1, comprising in combination with the casing and the blade- or vane-wheel, a rack swivelly mounted on the casing, a tooth wheel engaging with said rack, and a spring adapted to 20 maintain said wheel in mesh with said rack.

25 4. A powder box as specified in claim 1, comprising in combination with the box and the blade- or vane-wheel, a casing composed of two like parts guided rectilinearly surrounding said box the edges of said parts adapted to abut, and an element mounted on one of said casing parts adapted to actuate said blade wheel.

30 5. A powder box as specified in claim 1, comprising in combination with the powder container, a spring actuated mirror adapted to spring up, when the box is being opened.

BELA ROSENTHAL.
